UNITED STATES PATENT OFFICE.

CHARLES EDWARD RIEDEL, OF MOUNT CLEMENS, MICHIGAN, ASSIGNOR, BY MESNE ASSIGNMENTS, TO DAYTON SCALE COMPANY, OF DAYTON, OHIO, A CORPORATION OF NEW JERSEY.

SCALE.

Application filed November 10, 1919. Serial No. 336,926.

To all whom it may concern:

Be it known that I, CHARLES EDWARD RIEDEL, a citizen of the United States of America, residing at Mount Clemens, in the 5 county of Macomb and State of Michigan, have invented certain new and useful Improvements in Scales, of which the following is a full, clear, and exact description.

This invention relates to certain new and 10 useful improvements in scales and is particularly directed to an improved platform lever system.

Among the objects of my invention are the provision of a platform lever system which 15 will be compact and at the same time provide a multipoint support for the goods platform; a further object of my invention resides in the provision of a system of such character that the use of checks and like 20 devices for maintaining the platform horizontal is obviated. Other objects reside in the provision of a system of levers which will operate with a minimum of friction and drag. Other objects will be set forth in 25 detail in the accompanying specification and drawings.

In the drawings Figure 1 shows a perspective view of my improved base lever system with the platform broken away to show the 30 levers.

Fig. 2 shows a top plan of the base levers with platform and platform frame removed.

Fig. 3 shows a longitudinal section taken on line 3—3 of Fig. 2.

Fig. 4 shows a detail rear end view of the 35 main lever.

The scale to which my invention is shown as applied is of the computing drum type with springs to resist the movement of the 40 levers. A scale of this general type is shown and described in detail in my Patent 1,355,499, and the details of the thermostat and connections to the drum and springs are found in the patent of King and Burkeiser, 1,353,997. These details form no 45 part of my present invention.

In the present embodiment 10 is the base of the scale having at the rear an upright pedestal 11 which supports the drum (not 50 shown) and provides a housing for the connections to the springs and indicating drum. Upon the forward end of the base is secured a bracket 12 having posts which support bearings for the front pivots 13 of the main 55 scale lever 14. This lever is substantially

Y-shaped having integral therewith an H-shaped stiffening and pivot-supporting frame comprising cross-members 15, 16 and 17. The Y-shaped lever also carries a thermostat T and has an end 18 extending rearwardly into the pedestal where connections to the springs and indicating devices are made in the manner set forth in the copending application of King and Burkeiser, Serial No. 126,648, filed October 20, 1916. 60

The Y-shaped lever also carries outwardly extending upwardly pointing intermediate pivots 19 which support link bearings 20 and also carries on intermediate arm 16 an intermediate pivot 22 which supports link bearing 23. Underlying the main Y-shaped lever 14 is an auxiliary B-shaped lever 24 (see Fig. 2), having the side arms thereof parallel to outside and below the side arms of the Y-shaped lever, as shown in Figs. 1, 70 2 and 3. The cross member 25 of auxiliary lever 24 carries a suitable pivot which cooperates with link bearing 23, whereby the auxiliary lever is pivotally supported at a single point upon the main lever. Auxiliary 75 lever 24 also carries pairs of upwardly pointing outwardly extending pivots 26 at the forward end thereof and similar pairs 27 at the rearward end of the lever.

Pivots 27 co-operate with link bearings 28 80 which are swiveled to plates 29 fastened to the base 10 of the scale. The links 28 form a swinging fulcrum for the auxiliary lever 24.

A substantially I-shaped platform support 30 straddles both levers 14 and 24 at the forward end and projects between the arms of lever 14 and the arm of lever 24 at the rearward end as clearly shown in Fig. 2. The I-shaped platform support has 90 integral posts 31 which support at their upper ends a skeleton frame 32 which in turn supports the glass plate 33 which forms the platform of the scale. 95

The ends of rearwardly extending arms of the I-shaped platform support have plates fastened thereto to which are swivelled the link bearings 20. At the front ends of the arms of platform support 30 are similar plates to which link bearings 34 are 100 swivelled. The bearings of the links co-operate with the knife edge pivots 26 which are mounted upon the forward ends of the auxiliary lever 24. The movement of the parts will be readily understood from the 105 110

foregoing description. It may be stated, however, that the weight of the goods is transmitted to four points—namely, the ends of the arms of the platform support. 5 The force is then divided, one portion being exerted through links 19 directly upon the main lever 14. The other part of the force is transmitted through links 34 to the auxiliary lever which in turn, through link bearing 23, transmits a proportionate part of the applied force to main lever 14. Lever 14 is a lever of the third order and auxiliary lever 24 is a lever of the second order.

By referring to Fig. 2 it will be seen that 15 pivots 27 are in vertical alignment with pivots 19 and pivots 13 are in vertical alignment with pivots 26. This arrangement gives a more stable support for the platform.

20 The construction set forth which provides for the application of the forces in the manner explained provides an extremely stable support for the platform and obviates the use of the check which is commonly used to 25 maintain the platform in horizontal position. At the same time friction is minimized and the parts are extremely compact permitting the use of a shapely and low housing for the base lever system.

30 What I claim and desire to secure by Letters Patent of the United States is:

1. In a scale in combination, a main scale lever having a pair of fulcrum pivots at one end thereof and intermediate pivots, said 35 intermediate pivots comprising a pair of platform supporting pivots and a single pivot intermediate the platform pivots and the fulcrum pivots, an auxiliary lever having a pair of fulcrum pivots at one end 40 thereof, a pair of platform pivots at the opposite end thereof in vertical alignment with the fulcrum pivots of the main scale lever, and a single intermediate pivot, and means for suspending the auxiliary lever 45 from the main lever, said means comprising a connecting means co-operating with the aforesaid single intermediate pivots.

2. The invention set forth in claim 1 in 50 which a platform support is pivotally supported upon the intermediate pivots of the main lever and the end pivots of the auxiliary lever.

3. In a scale, in combination, a main scale lever having a pair of fulcrum pivots 55 at one end thereof and intermediate pivots, said intermediate pivots comprising a pair of platform supporting pivots and a single pivot intermediate the platform pivots and the fulcrum pivots, an auxiliary lever having a pair of fulcrum pivots at one end 60 thereof, a pair of platform pivots at the opposite end thereof, and a single intermediate pivot, means for suspending the auxiliary lever from the main lever, said 65 means comprising a connecting means co-

operating with the aforesaid single intermediate pivots, and a platform support, said platform support having a pair of swinging bearings cooperating with the forward pair of pivots on the auxiliary lever, and a pair 70 of swinging bearings cooperating with the pair of intermediate pivots on the main lever whereby said platform support is pivotally supported on the main and auxiliary levers. 75

4. In a scale, in combination, a main scale lever having a pair of fulcrum pivots at one end thereof, and intermediate pivots, said intermediate pivots comprising a pair of platform supporting pivots and a single pivot intermediate the platform pivots and the fulcrum pivots, and an auxiliary lever having a pair of fulcrum pivots at one end 80 thereof, said fulcrum pivots consisting of a pair of swinging bearings, a pair of platform pivots at the opposite end of said auxiliary lever, and a single intermediate pivot, means for suspending the auxiliary lever from the main lever, said means comprising a connecting means cooperating 85 with the aforesaid lever pivots, a platform supported upon the main and auxiliary levers, and means for pivotally supporting said support upon said levers comprising pairs of swinging bearings cooperating with the end pair of pivots on the auxiliary lever and the intermediate pair of pivots on the auxiliary lever. 90

5. In a scale in combination, a Y-shaped main lever having two pairs of pivots projecting outwardly from the Y-arms, one pair on the ends of the arms forming a lever support and the second pair disposed intermediate the ends of arms forming 100 points of support for a platform support, H-shaped cross members integral with said main lever, an auxiliary lever of substantially B-shape, means for supporting the B-shaped auxiliary lever by the main lever, said means comprising a swinging bearing connection co-operating with a pivot on the cross-member of the B-shaped lever with a pivot on the H-shaped cross-member of the Y-shaped main lever and a platform support pivotally supported upon the main 105 and auxiliary levers. 110

6. In a scale in combination, a Y-shaped main lever having H-shaped cross-members, said lever having fulcrum pivots at one end and having a pair of intermediate pivots and also a single intermediate pivot, a B-shaped auxiliary lever having a pair of fulcrum pivots at one end, a pair of pivots at the opposite end, and a single pivot intermediate the ends, means for suspending the B-shaped lever from the Y-shaped main lever, said means comprising a swinging bearing co-operating with the single intermediate pivot on the main lever and the single intermediate pivot on the auxiliary 115 120 125 130 135

B-shaped lever, and an **I**-shaped platform support pivotally supported upon the pair of intermediate pivots upon the main lever and the pair of end pivots on the auxiliary lever.

7. In a scale in combination, a main lever having a plurality of arms, said lever being pivoted at the ends of said arms, an auxiliary lever having arms extending substantially parallel with the arms of the

main lever, said lever being fulcrumed at one end thereof, and being pivotally connected with the main lever, and a platform support pivotally supported upon the auxiliary lever and having arms straddling the 15 arms of said lever and pivotally supported by the main lever arms.

In testimony whereof I hereunto affix my signature.

CHARLES EDWARD RIEDEL.
